WORK HANDLING APPARATUS FOR
MECHANICAL PRESSESWilliam G. Landwier, Wellsville, N. Y., assignor
to The Air Preheater Corporation, New York,
N. Y.

Application August 20, 1941, Serial No. 407,568

1. Claim. (Cl. 153—21)

The present invention relates to mechanical presses for performing operations on metal plates or the like and particularly to apparatus for handling the work piece.

When long steel plates are worked upon in a press, as to form a flange along one edge, the major part of the plate overhangs the die and projects outwardly from the press where it usually rests upon a supporting table. When the plate is struck by the punch of the press the outer end of the plate flies upwardly as the punch strikes. Unless the outer end of the plate is held in this new position, it will drop back to its original level when the punch is released. This is obviously a dangerous condition since it imperils the workmen attending the press. Sometimes it is found necessary to strike the plate again to perfect or complete the operation and in such instances it is necessary to hold the outer part of the plate in its raised position in readiness for the re-striking operation. Heretofore a block and tackle has been utilized, attaching one end of its rope to the outer end of the plate and having one or more men maintain the rope taut so as to compensate for the movements of the plate. This, however, is not entirely satisfactory as among other things it requires the services of additional workmen.

The present invention provides an automatic handling device for work pieces on which operations are performed in mechanical presses or similar equipment. Essentially the invention contemplates attaching the lower end of a cable to the outer end of the plate with the upper end of the cable connected to an arm that projects from the front of the press and which is maintained under torque by suitable apparatus acting to swing the arm upwardly to take up the slack produced in the cable as the outer end of the plate flies upwardly.

The present invention will be best understood upon consideration of the following detailed description of an illustrative embodiment thereof when read in conjunction with the accompanying drawing in which:

Figure 1 is a perspective view of a press embodying the plate handling device of the present invention; and

Figure 2 is a front elevational view, partly in section, of the upper part of the press illustrating apparatus for traversing the arm of the work-handling device across the front of the press.

In Figure 1 there is illustrated part of a mechanical press having a punch or working blade 10 which is moved downwardly under great pres-

sure to force part of a work piece in the form of a plate 12 against an anvil or die 14 so as to form a flange along the inner edge of the plate. When positioned to be struck by the punch 10, plate 12 rests horizontally with a part thereof along its inner edge between the punch 10 and die 14 and the greater part of the plate projects outwardly away from the press and rests on a table 15 or other suitable supports. In accordance with the present invention a cable 16 is attached to the outer end of the plate as by means of a hook 17, ring 18 and a clamp 19 applied to the plate. Cable 16 passes over a sheave 20 carried on a rock arm 22 projecting outwardly from the upper part of the framework of the press. At its other end cable 16 is attached to the drum of a winch 24 driven by a reversible motor 25 so that the length of the cable paid out from the winch may be adjusted to the amount required for attaching it to the plate. The winch 24 is provided with a suitable brake (not shown). The arm 22 is carried by a bracket 26 keyed to a rock shaft 28 for rotation therewith. As shown in Figure 2, the bracket 26 is provided with a threaded lug 30 through which a threaded spindle 32 extends so that on rotation of the latter bracket 26 may be traversed across the front of the press so as to locate the arm 22 and cable 16 in the desired position.

Various mechanisms might be employed for maintaining torque upon shaft 28 to tension the cable 16 so as to take up the slack in the latter as the end of plate 12 flies upwardly. For illustrative purposes Figs. 1 and 2 show a sector plate 34 secured to shaft 28 and having attached thereto one end of a cable 36 whose other end is connected to the piston rod 37 of an air motor 38 to which compressed air is supplied through an air line 39. Associated with shaft 28 at its other end is a one-way clutch and brake 40 which acts to hold the arm 22 in its raised position when the outer end of plate 12 flies upwardly. Any suitable form of releasable brake such as shown in the U. S. Patent 757,668, issued April 19, 1904, may be utilized; in Figure 1 there is illustrated a release cord 42 for the brake 40.

Briefly described the operation is as follows: When a plate 12 is to have a flange formed along its inner edge the latter is positioned between the punch 10 and die 14 with the major portion of the plate resting on the table 15. Clamp 19 is mounted at the outer edge of the plate and connected by ring 18 to the hook 17 at the lower end of cable 16, winch 24 having previously been operated to pay out as much cable as required.

At this time the arm 22 is in its lower position, usually horizontal. When compressed air is admitted to the air motor 38 torque is transmitted through cable 36, sector 34 and shaft 28 to arm 22 with the result that cable 16 is maintained under tension. Consequently, when the punch 10 strikes the plate 12 and the outer end of the latter flies upwardly, the resulting slack in cable 16 is taken up as the arm 22 is moved clockwise under the torque applied thereto by the air motor 38. At this time the brake 40 prevents reverse movement of arm 22 and obviates oscillations of the outer end of the plate 12 and holds it in its upper position even though the supply of air to the motor 38 might be cut off. Hence, a second striking operation, if required, may be performed to complete the operation because the outer part of plate 12 does not fall back on table 15.

When it is desired to remove the plate from the press, the punch 10 is raised and the winch 24 may be operated to pay out cable 16 so as to lower the plate. Alternatively, the supply of air to the air motor 38 may be cut off and its piston cylinder vented. Thereupon the brake 40 may be released by means of the cord 42 so as to permit arm 22 to turn counterclockwise, thereby allowing the outer part of the plate to fall back upon the supporting table.

Although an illustrative embodiment of the invention has been described in detail herein, there are many changes and variations that may be made without departing from the essentials of the invention and, therefore, it is desired and intended to include all such changes and variations within the scope of the appended claim.

What I claim is:

In a mechanical press or the like having a punch and die for performing an operation on a work piece partly mounted on the die with the major portion of the work piece projecting outwardly from the press, wherein engagement of the punch against the work piece causes the outer end of the latter to fly upwardly; an arm pivotally mounted on the press above its punch and die and projecting outwardly from the press in the same direction as the work piece; a cable connected to said arm and also to said work piece adjacent its outer end; and means continuously applying an upwardly directed force to said arm so as to rock it upwardly for taking up the slack produced in said cable as the outer end of the work piece moves upwardly when the work piece is struck by said punch.

WILLIAM G. LANDWIER.
